UNITED STATES PATENT OFFICE.

ARTHUR R. LOWE, OF CHICAGO, ILLINOIS, ASSIGNOR TO THE WESTERN SHADE CLOTH COMPANY, OF CHICAGO, ILLINOIS, A CORPORATION OF ILLINOIS.

PROCESS FOR TREATING SHADES AND THE LIKE.

1,203,758.

Specification of Letters Patent.

Patented Nov. 7, 1916.

Application filed January 22, 1915. Serial No. 3,788.

To all whom it may concern:

Be it known that I, ARTHUR R. LOWE, a citizen of the United States of America, residing at Chicago, county of Cook, and 5 State of Illinois, have discovered a certain new and useful Process for Treating Shades and the like, of which the following is a description.

My invention belongs particularly to that 10 part of the manufacture of window shades and similar articles where the fabric is treated with a suitably prepared filling, and thereafter completed and finished for the market.

15 It consists in the novel steps hereinafter particularly pointed out and described, and more particularly set forth in the claims.

In the drawings, wherein like reference 20 characters indicate like or corresponding parts, Figure 1 is a fragment, showing a shade finished in accordance with my improved process; Fig. 2 is a modification of the same; Fig. 3 is another modification; Fig. 4 illustrates the position and construction 25 of the preliminary rolls through which the shade passes in applying the filling, and Fig. 5 shows the rolls where the filling process is completed.

In the construction of shades it is common 30 after treating the fabric to pass the same through between suitable rolls, at the same time applying to the fabric a filling material suitably colored or tinted. The rolls firmly press the filling material into the 35 fabric, which is thereafter passed over suitable dry cans or calendar rolls, where it is dried, polished and finally delivered practically completed and ready for the market. Shades manufactured in this manner are 40 substantially of uniform color and without any predetermined design upon them, that is, being of one solid color.

In my improved process, I so construct 45 one or both rollers, through which the material is preliminarily passed and filled, that the pressure varies upon different parts of the fabric, that is, the pressure will be much heavier on certain predetermined portions of it than upon the other portions of it, so 50 that at those points where the pressure is heaviest the pressure will cause less filling to be taken up, or a thinner coating of the filling applied to the fabric, as it is by pressure forced into the adjacent parts 55 where there is less pressure. At the points

where the pressure is not so great there will therefore be a thicker coating of the material. Thus, for example, as shown in Fig. 4, the roll 1 may be of any preferred size, and in practice may be rubber or other suitable 60 material for the purpose, while the roll 2 is of brass or other suitable material, so constructed as at 3—3, etc., as to be raised, while the intervening parts 4 will be depressed.

65 5 is the furnishing roll, and 6 a trough, in which said roll is positioned, and which is charged with the filling material. The rollers may be operated by any preferred mechanism.

70 7 is the shade fabric passing through between the rollers (raised to throw the roller construction).

75 It will be obvious that those parts of the shade passing over the parts 3 will be subjected to much heavier pressure than those parts passing over parts 4, and that there will therefore be a heavier coating of the filling material on the parts that have passed over the depressed portion of the rollers, as at 4. 80 This particular instance will result in the shade having a striped appearance, because of the difference in the filling therein. After the shade has passed through the rollers it is so treated as to set the filling, as by heating or drying, or any other preferred manner, and may then be finished in the usual manner, and when finished retains the said striped appearance. In the preferred form, however, the shade, after passing through 85 the first rollers mentioned, and when the filler is set and the material is in suitable condition therefor, is then passed through between another pair of rolls preferably a plurality of times, substantially as shown 90 in Fig. 5, in which the rolls 8—8 are provided with straight faces, giving a uniform pressure on the shade.

9 9 is the furnishing or dope roller, and 10 the filling or dope trough.

100 It will be obvious that a filling of slightly different color or tint applied to the shade will result in filling the thin places 3 on the shade to the same extent as the coating is on the strip 4, and passing through between the rollers 8—8, the shade will be supplied with a suitable quantity of filler, which will then be of uniform thickness throughout. The shade is then dried, polished and finished in the usual manner,

110

giving the effect referred to, and as shown in the drawings. In practice it is found that even if the filling material used the second time is of the same color the striped 5 effect is still apparent in the finished shade.

It is obvious that the form of the roll 2 may be modified in various ways, as to the 10 location of the depressed portions, as well as their width as compared with the high 15 parts, or suitable patterns may be formed on the said roll, as indicated in Fig. 3.

In carrying my process into effect, I have secured satisfactory results by using a well known filling material composed of suitable 15 quantities of kaolin, flour and starch, suitably prepared and mixed together in a well known manner, and with the rolls so formed that when the shade has passed through the first treatment indicated in Fig. 20 4, and the filling set, there is a difference in the thickness of the shade at the two points from one-thousanthd to three-thousandths of an inch.

In carrying my process into effect upon 25 such products as window shades, I prefer to pass the same through the secondary rolls shown in Fig. 5 a plurality of times, after the fabric has been passed through the first rolls and the operation completed, 30 as herein set forth. I have secured entirely satisfactory results by passing the shades through the secondary rolls twice, and in such case I prefer to turn the shade the other side up in passing it through the secondary rolls the first time and reversing it again in passing through said rolls the last time. This results in giving the shade two coats from the bottom surface and one coat from the top. Obviously this operation may 35 be continued or repeated as desired. The fabric employed is of sufficient porosity or looseness of weave to permit the same to be thoroughly filled with the mixture by the several operations described. Of course 40 it will be understood that in using the word shades herein I do not mean to be understood as limiting my process to use upon shades alone, but wish to be understood as employing it upon any desirable fabric de- 45 sired for any preferred use.

Obviously, the coloring of the filling material may, in all cases, be modified as desired, and also that the rollers may be modified to form any desired design upon the 50 shade.

When suitably treated according to my process the shade will appear to be formed

from two different styles of weaving or material, giving it the pattern effect referred to, making it very attractive and salable. 60

Having thus described my invention, what I claim as new and desire to secure by Letters Patent is:

1. The herein described process of manufacturing shades and the like, consisting in 65 applying a suitable filling material to a properly prepared fabric, and then applying pressure thereto, said pressure varying at different parts of the fabric, whereby the body of the filler in the fabric also varies 70 at different parts thereof, and thereafter finishing the shade in the usual manner, to produce a uniform smooth surface.

2. The herein described process of manufacturing shades and the like, consisting in 75 applying a suitable filling material to a properly prepared fabric, and then applying pressure thereto, said pressure varying at different parts of the fabric, whereby the body of the filler also varies at different 80 parts of the fabric, and thereafter applying more filler thereto, and subjecting the same to a substantially uniform pressure, whereby the body of the filler in the fabric is also made substantially uniform. 85

3. The herein described process of manufacturing shades and the like, consisting of applying a suitable filling to properly prepared fabric, and applying pressure thereto, the pressure varying at different parts thereof, and thereafter applying more filler of a slightly different color to the fabric, and subjecting the same to a uniform pressure, and finishing the shade in the usual manner. 90

4. The herein described process of manufacturing shades and the like, consisting in applying a suitable filling material to a properly prepared fabric, and then applying pressure thereto, said pressure varying at different parts of the fabric, whereby the body of the filler also varies at different parts of the fabric, and thereafter treating the filled fabric a plurality of times by applying more filler thereto and subjecting the same to a substantially uniform pressure, 100 whereby the body of the filler in the fabric is made substantially uniform. 105

In testimony whereof, I have hereunto signed my name in the presence of two subscribing witnesses.

ARTHUR R. LOWE.
